UNITED STATES PATENT OFFICE

ROBERT T. FRAZIER, OF CHATTANOOGA, TENNESSEE, ASSIGNOR TO TENNESSEE FURNITURE CORPORATION, OF CHATTANOOGA, TENNESSEE, A CORPORATION OF TENNESSEE

REFRIGERATOR

Application filed December 19, 1932. Serial No. 648,001.

This invention is a novel improvement in refrigerators of the ice box type, and the principal object of the invention is to provide means for maintaining a low temperature evenly distributed throughout the interior of the refrigerator.

Heretofore the great difficulty encountered in domestic refrigeration has been in maintaining a low temperature evenly distributed throughout a refrigerator. This is true even of electric refrigerators, but presents a much more serious problem in refrigerators cooled by ice. In ice refrigerators now in general use it is very difficult to attain low temperatures during warm weather, and in an ordinary side-icer, when the exterior temperature is 80° F., the lowest interior temperature attained is about 50° F. at the center of the milk compartment, immediately under the ice chamber, and about 60° to 64° F. at the warmest place in the box, i. e., at the top shelf of the provision compartment beside the ice chamber. By building a very heavily constructed and well insulated ice refrigerator, it is possible at such exterior temperature, during the same weather conditions, to attain a temperature of 42° F. in the milk compartment, and 52° F. at the top shelf in the provision compartment.

A medium type refrigerator, using the cheaper board type insulation, will usually show temperatures of around 48° F. in the milk compartment, and 60° F. at the top shelf. Various means, such as special baskets for supporting the ice, special flues, and special ice bottoms have heretofore been developed for attaining lower temperatures, but such means have not been successful. I have found that the prime reason for the high temperatures was the sluggish circulation of air within the refrigerator, which condition could not be improved, nor the air circulation stimulated on a thermo-siphonic basis.

The necessity of maintaining the temperature inside a refrigerator below 50 is generally conceded. This condition is possible in electric refrigerators by reason of the low temperatures of evaporation of the gas plus the thermostatic control. In ice refrigerators however, the temperature varies very

widely, first, because of the great differential of from 10 to 12° F. between the temperatures at the bottom of the refrigerator and at its top; and secondly, because of the variation of temperature due to the decrease in size of the cake of ice as it melts. The rate of exchange of heat from ice to air varies in direct proportion to the surface area of the ice which is exposed to the air. Hence a 50 lb. cake of ice will require as long a time in melting in the open air, or in air of any given velocity, as a 100 lb. cake along side of it under the same conditions. This is due to the fact that as the surface area of the ice is reduced a slower circulation of air in the refrigerator is produced, and moreover the slowly moving air has a higher temperature. Therefore, temperatures of 47° to 54° F. beneath the ice chamber, and from 59° to 66° F. on the top shelf, depending upon the amount of ice in the refrigerator at the time, are quite usual.

The primary object of my invention is to correct this temperature deficiency in ice refrigerators, by providing means for increasing the volume of air flowing over the ice as the surface area of the ice is decreased; also, to reduce the temperature differential between the top and bottom of the refrigerator by providing means for increasing the speed of circulation of the air inside of the cabinet. By my invention, a temperature of 40½° F. is readily produced inside the bottom or milk compartment of the refrigerator, and a temperature as low as 43° F. on the top shelf, due to the increased speed of circulation of the air, and increased rate of heat exchange from the ice to the air.

A still further object is to provide an electric fan operated by a thermostat set to close the fan circuit when the temperature is about 50° F. in the warmest part of the refrigerator, and to open the circuit when about 46° F. is attained, whereby the temperature in the bottom of the refrigerator will remain at about 42° F. substantially continuously.

I will explain the invention with reference to the accompanying drawing which illustrates one practical embodiment thereof to enable others to adopt and use the same; and

will summarize in the claims, the novel features of construction, and novel combinations of parts, for which protection is desired.

5 The drawing is a transverse section through a refrigerator of the side-icer type showing the arrangement of fan and thermostat with respect to the flues of the refrigerator compartments.

10 The refrigerator may be of any desired type adapted to hold ice, and preferably the casing 1 is heat insulated. In the embodiment shown in the drawing the interior of the refrigerator contains an ice chamber 2 in one upper corner for receiving the cake of ice 3 in the usual manner, the ice chamber being formed by the usual lining, having a bottom 4a and side wall 4b, separating the ice chamber from the main portion of the 15 refrigerator. In the bottom 4a of the lining is a flue 4c leading into the milk compartment 5 disposed immediately below the ice chamber, and in the upper portion of the side wall 4b is a flue 4d leading into the top 20 of the provision compartment 6.

In the flue 4d is an electric fan 7 adapted to force the warmer air at the upper end of the provision compartment 6 through flue 4d and down upon the ice 3 in the ice chamber, and downwardly through the flue 4c in the bottom of the ice chamber 2 into the milk compartment 5, the chilled air circulating through the chambers 5 and 6, in the direction of the arrows, and back again to the 35 ice-chamber 2, the forced circulation maintaining the temperatures in the compartments 2, 5 and 6 substantially the same.

The fan 7 is controlled by a thermostat 8 arranged in the electric lead wires 9, which 40 thermostat 8 is preferably adjusted to close the fan circuit when a temperature of 50° F. is reached in the top of the provision chamber 6, and to open the circuit at 45° F. The temperature in a medium insulated ice box 45 was actually lowered to 41 $\frac{3}{4}$ ° F. in the milk compartment 5, and 45° F. on the top shelf in compartment 6.

The fan 7 will operate about five minutes and remain idle about twenty-six minutes 50 when the room temperature is constantly at 80° F. Obviously, when the room temperature is lower than this, the "off" periods will be longer. When the room temperature is higher than 80° the "off" periods will be 55 slightly shorter. As the ice melts, there is a slight increase in length of the running time during the "on" periods which automatically offsets the slower rate of transfer due to the decreased area of the ice. By extending the operation of the fan 7 for as long a period as 25 minutes, the temperature was reduced to 40° F. in the milk compartment 5, and 43° F. at the top shelf in compartment 6, temperatures never before attained or maintained in ice refrigerators.

The temperature differential between the bottom of the box and the top of the box may thus be reduced as low as 3° F. by my invention, whereas heretofore it had been considered impossible to get it lower than 9 or 10° F. in the most expensively constructed refrigerators.

The electric leads 9 may be ordinary rubber covered extension cords adapted to plug in any electric light socket. The motor being less than a 20th of a horse-power, consumes less current than an ordinary 40 watt light, and develops very little heat in the refrigerator due to the extremely short cycle 75 operation required of it.

80 Actual tests have shown that with a thermostatically operated fan in the refrigerator the increase in ice consumption in the cheaper board type insulated ice box of 100 pounds capacity was only 6 pounds per 24 hours and I was able to maintain the temperature between 46 and 50° F. in the warmest part of the refrigerator continuously up 85 until the time there was only 10 pounds of ice left in the box. The same refrigerator without the fan in it showed a temperature in the warmest part of 63° when there was still 44 pounds of ice in the refrigerator. My invention therefore provides novel and useful features in an ice refrigerator as it offers low temperature, economical refrigeration to those who cannot afford electric refrigerators as well as to those who prefer ice refrigerators because of their obvious 90 advantages.

95 I claim:—

100 1. In a refrigerator, having an ice chamber in the upper portion and having a food compartment and having flues connecting the ice chamber and compartment; means for 105 circulating air through the compartment and ice chamber, and means for automatically varying the volume of circulating air in inverse proportion to the surface area of the ice.

110 2. In a refrigerator as set forth in claim 1, said automatic means comprising a thermostat disposed in the warmest portion of the food compartment.

115 3. In a refrigerator, having an ice chamber in the upper portion and having a food compartment below or to one side of the ice chamber and having flues connecting the ice chamber with the compartment; means adapted to circulate air through the ice chamber and food compartment, and means for automatically operating the air circulating means within predetermined temperature limits.

120 125 4. In a refrigerator as set forth in claim 3, said automatic means comprising a thermostat disposed in the warmest portion of the food compartment.

130 5. In a refrigerator, having an ice chamber in the upper portion, and having a milk

compartment below the ice chamber, and having a food compartment beside the ice chamber, and having flues connecting the ice chamber with the milk and food compartments respectively; an electric fan in the food compartment flue adapted to circulate air upwardly through the ice chamber and upwardly through the compartments, and means for automatically opening and closing the fan circuit within predetermined temperature limits.

6. In a refrigerator as set forth in claim 5, said automatic means comprising a thermostat disposed in the upper portion of 15 the food compartment.

7. In a household refrigerator having an ice chamber and a food compartment, and having flues connecting the ice chamber and the compartment; means for circulating air 20 through the compartment and the ice chamber, and means for automatically varying the volume of circulating air in inverse proportion to the surface area of the ice.
